UNITED STATES PATENT OFFICE.

ARTHUR ROBERTS, OF EVANSTON, ILLINOIS, ASSIGNOR, BY MESNE ASSIGNMENTS, TO CHICAGO TRUST COMPANY, TRUSTEE, OF CHICAGO, ILLINOIS, A CORPORATION.

TAR SEPARATOR AND REGULATOR FOR THE SAME.

Application filed July 6, 1920. Serial No. 394,305.

To all whom it may concern:

Be it known that I, ARTHUR ROBERTS, a citizen of the United States, residing at Evanston, in the county of Cook and State 5 of Illinois, have invented certain new and useful Improvements in Tar Separators and Regulators for the Same, of which the following is a specification.

This invention has reference to improvements in tar separators and regulators for 10 the same. The invention has to do with the construction of the regulator itself and the combination of the same with the tar separator, and also with the construction of 15 the tar separator itself.

In order that the features of the invention may be more easily understood, I will first explain briefly the general construction of 20 the tar separator and its mode of operation, and will then explain the construction and operation of the regulator and the manner 25 of its combination with the separator.

One of the features of the invention concerns itself with the construction of the tar 30 separator. In this connection an object is to provide a tar separator of such form that the separation or removal of the tar from the gases is effected by causing the gases to be drawn through a series of relatively small orifices under such pressure and velocity 35 that the contained tar will be precipitated, so that it will run down over or can be removed from said surfaces. In this connection it may be stated that the effectiveness, 40 with which the tar will be thus removed, will depend largely upon the velocity at which the gases are drawn or forced through the relatively small orifices aforesaid; and this in turn will depend largely upon the 45 pressure existing on the two sides of the plate or element through which the orifices pass. In case the volume of gas flowing through the orifices changes, it will be evident that the pressure will also change and 50 also the volume of gas passing through each orifice, so that if the velocity of the gases flowing through the orifices is to be maintained constant or substantially constant, it will be necessary to vary the number or amount of the orifices from time to time according to the changes in said gas volume.

One of the features of the invention has to do with the provision of a construction of separator wherein the gases are passed through a plate or plates extending in a 55 more or less vertical fashion and provided with a series of relatively small orifices at different vertical elevations, in combination with a container or vat within which tar may be contained so that the elevation of said tar 60 will control the number or amount of orifices exposed to the passage of the gas by cutting off more and more of the surfaces of said orifices as the elevation of the tar within the container or vat is raised. 65

The automatic regulation of the said separator for the purpose of ensuring a substantially uniform pressure on both sides of the plate or plates may, therefore, be secured by causing the tar to either rise or fall within 70 said container; and this adjustment or variation of the elevation of the tar surface may be made either automatic, or manual, or combined, as desired.

Another feature of the invention has to 75 do with the provision of means whereby the regulation of the level of the tar surface may be varied either manual, or automatic, or by a combination of these two; and in this connection to provide an arrangement 80 whereby when automatic regulation is to be secured, the regulator itself may be adjusted from time to time so as to maintain a predetermined and selected differential of pressure within the apparatus. 85

Other objects and uses of the invention will appear from a detailed description of the same which consists in the features of construction and combinations of parts hereinafter described and claimed. 90

Referring to the drawings:

Figure 1 shows a side elevation of a tar separator embodying certain features of the present invention, the tar separator in this figure being shown disassociated from the 95 automatic regulating mechanism;

Fig. 2 shows a top plan view corresponding to Fig. 1;

Fig. 3 shows a horizontal section taken on line 3—3 of Fig. 1, looking in the direction 100 of the arrows;

Fig. 4 shows a side elevation of a tar sep-

arator having attached thereto a regulator embodying the features of the present invention;

Fig. 5 shows a view similar to Fig. 4, 5 with the exception that Fig. 5 is taken at right angles to Fig. 4;

Fig. 6 shows a detailed elevation of a regulating device;

Fig. 7 shows a vertical cross section of the 10 construction shown in Fig. 6, being at right angles to the position of Fig. 5; and

Fig. 8 shows a top plan view corresponding to Figs. 6 and 7.

I will first describe the construction of tar 15 separator shown in detail in Figs. 1, 2, and 3, and will then explain the construction of regulator which I have illustrated in conjunction with the separator.

The separator proper comprises a tank 10 20 generally of cylindrical form, and provided with top and bottom closures 11 and 12. Ordinarily a horizontal partition 13 will be located across the lower portion of the tank to provide a manifold or the like 14 in said 25 lower portion. A gas inlet connection 15 serves to deliver the untreated gas into said manifold.

Extending upwardly from the partition 13 is a series of tubes or pipes 16, the upper 30 ends of which are generally open. Extending down over each of these tubes or pipes is an enclosed screen or plate 17 whose upper end is ordinarily closed, and as is clearly 35 evident from Fig. 1 the side walls of said plates or screens 17 are perforated usually with a large number of relatively small perforations. The various plates or screens 17 may be conveniently carried by a common 40 spider or frame 18 suspended by a rod 19 which extends through the top 11, said rod connecting by a chain 20 with a segment 21 on the lever 22 which is pivoted to a bracket 23 at a point 24. A rod 25 may be provided 45 having its upper end connected to the lever 22 and its lower end to a hand wheel 26 so that by turning said hand wheel the lever may be tilted or rocked in order to raise or lower the screens or plates 17 in unison.

The gas entering through the connection 50 15 and manifold 14 will pass up through the tubes or pipes 16 and through the plates or screens 17 into the space at the upper end of the tank whence it may be delivered through a delivery connection 27.

It will be evident that the number and 55 amount of the perforations exposed for the passage of gas through the screen or plates will depend upon the level of the liquid tar within the tank, and also the adjustment of 60 the screens or plates vertically.

Assuming that the screens or plates are fixed in a given vertical position, then the amount of said exposure will depend upon the elevation of the liquid tar in the tank 10.

65 The higher the said tar rises in said tank

the smaller the number and amount of perforations exposed, and consequently the smaller the volume of gas which may pass without rise of pressure; or conversely as the tar level is raised, the number and 70 amount of perforations exposed is decreased, so that the volume of gas must decrease in given proportion or else the pressure on the two sides of the plates or screens will increase.

I will now explain the construction of the regulator which I have illustrated. Said regulator is shown in detail in Figs. 6, 7, and 8, to which reference may first be had. This regulator includes a cylinder or tank 28 80 within which is carried oil or other suitable liquid at an elevation of perhaps one-half of its height, said elevation being conveniently shown in the gauge 29. The cylinder 28 has its top and bottom portions closed by the 85 cap plates 30 and 31 respectively.

Within the cylinder 28 is located an inverted bell 32 of light and gas-tight construction, and which is free to move up and down within the cylinder. A gas connection 90 33 communicates with a pipe 34 which extends upwardly within the bell to a point near its roof. Consequently the space within the bell is subjected to the pressure of the gas from the connection 33. Another connection 35 may be established in the upper portion of the cylinder 28, so that the outside of the bell will be subjected to its pressure. Consequently the bell will tend to rise by the differential existing between said pressures.

A rod or stem 36 has its lower portion secured to the roof of the bell, and said lower portion may depend into the tube 34 and through a bearing 37 which assists in guiding the movement of the stem 36 up and down. The upper end of said stem 36 extends into and is secured to a cap 38 and a tube 39 depends downwardly from said cap to a point near the top closure 30 of the cylinder 28. A pair of tubes 40 and 41 extend upwardly from the cap plate 30 to a point near the location of the cap 38. The tube 40 is located inside of the vertically movable tube 39, and the tube 41 is outside of 115 said vertically movable tube, so that a liquid seal may be established for the tube 39 between the tubes 40 and 41, as by the use of mercury or other liquid. Mercury is desirable for this purpose since it has very 120 high specific gravity and makes it possible to seal against relatively heavy gas pressures with an apparatus of comparatively small height.

Adjacent to the apparatus just described is located a pair of pipes 42 and 43, one of which serves as an inlet connection for the conveyance of tar into the tank 10, and the other of which serves to convey the tar away from said tank. Ordinarily the pipe 42 will 125

be the inlet pipe and the pipe 43 the discharge pipe. Within these pipes are located valves 44 and 45 respectively, and for purposes of convenience in illustration, and also 5 because they are found to be very satisfactory in service, I have illustrated said valves as being of the butterfly type. They are well shown in elevation in Fig. 6.

The stems 47 and 48 from these butterfly 10 valves extend into a frame or the like 49 wherein they find convenient bearing, and are provided with the pinions 50 and 51 respectively. A gear 52 is pivoted in said frame, said gear meshing simultaneously 15 with the pinions 50 and 51. A lever arm 53 is secured to the gear 52 so that by rocking said lever arm, the butterfly valves 44 and 45 will be opened and closed or vice-versa in opposition to each other. That is to say, 20 the opening of one of these valves is simultaneously accompanied by the corresponding closing of the other. The cap 38 carries a cross member 54 which connects to the lever arm 53 by a pair of links 55 and 56, and 25 said lever arm is conveniently bifurcated in its central portion, as shown in Fig. 8, so that said central portion surrounds the aforesaid mercury or other seal. It is, therefore, evident that the rising and falling of 30 the bell 32 causes the opening and closing of the butterfly valves. A dash pot 57 may be provided for dampening the movements of the lever 53, the upper and lower ends of 35 said dash pot being connected by a pipe 59 which has the valve 60.

The regulator so far described may be provided with counter-weights 61 and 62 on the lever arm 53 by means of which adjustment it is possible to set the apparatus to 40 maintain at substantially uniform amount the differential pressure within wide limits.

The aforesaid inlet and outlet pipes connect into the tank 10 as clearly shown in Figs. 4 and 5, the pipe 42 ordinarily connecting at a relatively high elevation 63, and the pipe 43 ordinarily connecting at a relatively low elevation 64. It is, therefore, possible to 45 secure a wide range of regulation of the operating elevation of the tar within the 50 tank.

The connection 33 from the lower portion of the regulator leads by a pipe 65 to the inlet gas connection 15, and the connection 35 from the upper portion of the regulator leads by a pipe 66 to the outlet or delivery gas connection 26. With this arrangement the regulator will operate according to the differential pressure existing within the tank 10.

55 The operation of this combined arrangement will now be readily apparent. As the differential pressure increases, the bell 32 will rise, and the inlet butterfly 44 will close to some extent, and the outlet butterfly valve 45 will simultaneously open. The result will

be that a smaller amount of tar will be delivered into the tank 10 while at the same time the discharge of tar from said tank will be more readily accomplished, and the surface of the tar will fall. As this surface 70 falls, the number and amount of perforations in the screens or plates will increase, thereby permitting a more ready flow of gas and being accompanied by a reduction in differential pressure. The action will thus 75 be perfectly automatic, and the pressure will be maintained constant within very small limits of fluctuation.

I claim:

1. In a machine of the class described, tar 80 separating means comprising a tank, a series of fixed pipes upstanding from the lower portion of the same, a vertically movable bell over each of said pipes having in its side walls a series of relatively small perforations, means for manually adjusting the elevation of said bells with respect to said pipes, a connection for delivering gas simultaneously into the lower ends of all of said pipes, a connection for delivering gas from 85 the upper portion of the tank, and means for regulating the operation of said separator comprising a fluid inlet connection in the upper portion of the tank, a fluid outlet connection in the lower portion of the tank, 90 valves in both of said connections, and means for simultaneously causing an opening movement of one valve and a closing movement of the other valve operable according to the differential of pressure between the 95 inlet and outlet gas connections, substantially as described.

2. In a machine of the class described, tar 100 separating means comprising a tank, a series of fixed pipes upstanding from the lower portion of the same, a vertically movable bell over each of said pipes having in its side walls a series of relatively small perforations, a connection for delivering gas simultaneously into the lower ends of all of 105 said pipes, a connection for delivering gas from the upper portion of the tank, and means for regulating the operation of said separator comprising a fluid inlet connection in the upper portion of the tank, a fluid outlet connection in the lower portion of the tank, 110 valves in both of said connections, and means for simultaneously causing an opening movement of one valve and a closing movement of the other valve operable according to the differential of pressure between the 115 inlet and outlet gas connections, substantially as described.

3. In a machine of the class described, tar 120 separating means comprising a tank, a pipe upstanding from the lower portion of the same, a vertically movable bell over said pipe having in its side walls a series of relatively small perforations, means for manually adjusting the elevation of said bell 125 130

- with respect to said pipe, a connection for delivering gas into the lower end of said pipe, a connection for delivering gas from the upper portion of the tank, and means 5 for regulating the operation of said separator comprising a fluid inlet connection in the upper portion of the tank, a fluid outlet connection in the lower portion of the tank, valves in both of said connections, and means 10 for simultaneously causing an opening movement of one valve and a closing movement of the other valve operable according to the differential of pressure between the inlet and outlet gas connections, substantially as described. 15
4. In a machine of the class described, tar separating means comprising a tank, a pipe upstanding from the lower portion of the same, an encircling pipe surrounding the first 20 mentioned pipe and having in its side walls a series of relatively small perforations, a connection for delivering gas into the lower end of the upstanding pipe, a connection for delivering gas from the upper portion of 25 the tank, and means for regulating the operation of said separator comprising a fluid inlet connection in the upper portion of the tank, a fluid outlet connection in the lower portion of the tank, valves in both of said 30 connections, and means for simultaneously causing an opening movement of one valve and a closing movement of the other valve operable according to the differential of pressure between the inlet and outlet gas connections, substantially as described. 35
5. In a machine of the class described, tar separating means comprising a tank, a pipe within the same having in its side walls a series of relatively small perforations, a connection 40 for delivering gas into the lower portion of said pipe, a connection for delivering gas from the upper portion of the tank, and means for regulating the operation of said separator comprising a fluid inlet connection in the upper portion of the tank, a fluid outlet connection in the lower portion of the tank, valves in both of said 45 connections, and means for simultaneously causing an opening movement of one valve and a closing movement of the other valve operable according to the differential of pressure between the inlet and outlet gas connections, substantially as described. 50
6. In a machine of the class described, tar separating means comprising a tank having on its interior a partition provided with a series of relatively small perforations, gas connections in the upper and lower portions of the tank for introducing and withdrawing 55 gas from the tank, said gas passing through the perforations of said partition, and means for regulating the operation of said separator comprising inlet and outlet fluid connections into the tank, valves in 60 both of said connections, and means for simultaneously causing an opening movement of one valve and a closing movement of the other valve operable according to the differential of pressure between the inlet and outlet gas connections, substantially as described. 65
7. In a machine of the class described, tar separating means including a partition provided with a series of relatively small perforations, a container for tar or the like surrounding said partition, means for directing gas through the perforations of said partition, and means for regulating the elevation of the tar on said partition including connections for delivering tar into and removing tar from said enclosure, valves in said connections, and means for simultaneously causing an opening movement of one valve and a closing movement of the other valve operable according to the differential of pressure on the two sides of the partition, 75 substantially as described. 80
8. In a machine of the class described, tar separating means including a partition provided with a series of relatively small perforations, a container for tar and the like surrounding said partition, means for directing gas through the perforations of said partition, and means for regulating the elevation of the tar on said partition including connections for delivering tar into and removing tar from said container, valves in said connections, a vertically movable bell operable according to the differential of gas pressure on the two sides of the partition, 90 95 and a positive connection from said vertically movable bell directly to the valves for simultaneously and instantaneously moving the valves in opposite directions as the bell moves under the differential of gas pressure, 100 substantially as described. 105
9. In a machine of the class described, tar separating means including a partition provided with a series of relatively small perforations, a container for tar or the like surrounding said partition, means for directing gas through the perforations of said partition, and means for regulating the elevation of the tar on said partition including connections for delivering tar into and removing tar from said container, valves in said connections, a vertically movable bell operable according to the differential of gas pressure on the two sides of the partition, 110 115 and means for moving the valves simultaneously in opposite directions synchronously with the movements of the bell, whereby the amount of opening and closing movement of the valves is directly dependent upon the amount of vertical movement of the bell, 120 substantially as described. 125
10. In a machine of the class described, tar separating means including a partition provided with a series of relatively small perforations, means for directing gas 130

through the perforations of said partition, and means for regulating the elevation of the tar on said partition including connections for delivering tar into and removing tar from said container, valves in said connections, and means, operable according to the differential of pressure on the two sides of the partition, for simultaneously moving

the valves in opposite directions and synchronously with the changes of differential 10 of pressure, whereby the opening and closing movements of the valves are directly proportional to the differential of pressure at all times, substantially as described.

ARTHUR ROBERTS.
